(57) **CLAIM**

I claim the ornamental design for a heart-shaped ornament, as shown and described.

DESCRIPTION

FIG. 1 is a top right, front isometric view of a heart-shaped ornament showing my new design;

FIG. 2 is a bottom left, front isometric view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a bottom plan view thereof.

A design rear elevation view has been omitted, as it is a mirror image of the front elevation view of FIG. 3.

The portion of the heart-shaped ornament depicted in broken lines in the figures is for the purpose of illustrating environmental structure and forms no part of the claimed design.
